UNITED STATES PATENT OFFICE.

JAMES HENRY GEORGE, OF ORANGE, NEW JERSEY.

METALLIC BARREL.

Application filed August 2, 1927. Serial No. 210,172.

The present invention relates to improvements in metallic barrels and consists in certain improvements over my prior United States Patent No. 967,629, granted October 16, 1910, and re-issued under date of May 7, 1912 as No. 13,414.

The objects of the present invention are, in general, the same objects as stated in my prior patent aforesaid.

10 By the present invention, I aim to secure a stronger construction, a more secure lock between the barrel body and head and an improved joint between the body and head which will resist distortion to a greater degree and consequently prove more leak proof.

A further object of the invention is to achieve these purposes in a simply constructed barrel of inexpensive parts.

With the foregoing and other objects in view, the invention will be more fully described hereinafter, and will be more particularly pointed out in the claim appended hereto.

In the drawings, wherein like symbols refer to like or corresponding parts throughout the several views,

Figure 1 is a perspective view of an improved barrel constructed according to the present invention.

30 Figure 2 is a vertical section taken on the line 2—2 of Figure 1.

Figure 3 is a horizontal section taken on the line 3—3 of Figure 2.

Figure 4 is a perspective view of one of the staves.

35 Figure 5 is a similar view of the locking strip.

Figure 6 is an enlarged fragmentary view showing the chime construction.

40 Figure 7 is a section of a slightly modified form of construction.

The staves 5 are provided with the in-turned side edges 6 forming flanges which however do not extend the full length of the 45 stave, but said flanges stop short of each end of the stave as best shown in Figure 4. These flanges as will be seen are L-shaped in cross section and extend over the side portions of the body of the staves. The staves

50 in my form of barrel are preferably curved to about the same curvature as wooden staves used in the construction of the ordinary wooden barrels. This curvature may however be increased or diminished as desired.

55 I form in the staves on each side of the central portion thereof depressions or grooves

over which the hoops 8 extend, said hoops being provided with an inwardly extending rib 9 adapted to engage in the depressions 7, so as to lock the hoops on the barrel and also to more firmly unite the parts of the barrel together.

10 designates the locking strip which is formed with a central portion of a width to extend over the projecting flanges of two adjacent staves when said staves are in position to form the barrel, the strip being provided with the inwardly extending L-shaped flanges 11 on each side thereof, which engage around the flanges 7 of the staves, as most 70 clearly shown in Figure 3.

Preferably, and as shown, at one end the strip or locking device 5 is provided with a curled-up portion 12, in order that convenient means may be furnished to remove the locking device and replace the same when desired. The locking device is bar-like in form and is of a length substantially equal to the length of the flanges 6 on the staves.

75 In the assembling of the barrel a pair of 80 staves are brought with their edges in contact and a locking device 10 is slipped by a lengthwise movement over the flanges thereof. Other staves are then placed alongside of these and similarly locked in position by 85 means of the locking strips or devices until the barrel is completed. The hoops 8 may now be forced on until their interiorly projecting ribs engage the grooves in the staves whereby they are firmly held in position and 90 the staves locked against longitudinal movement.

13 are the heads or ends of the barrel which may be of any suitable and convenient form, and in the construction shown, these heads 95 are formed with their edges bent up to provide annular flanges 14 which, when the heads are in position, rest against the ends of the staves. As the flanges on the edges of the staves do not extend to the ends of the 100 staves, the end portions of these flanges form interior supports or shoulders for the head, as most clearly shown in Figure 2.

15 is a securing means for holding the heads in position. This means shown comprises a ring 16 of a size to closely fit over the end of the barrel and having the in-turned flange 17 which will pass within and engage the upturned flange 14 of the head. Preferably and as shown the ring 16 is provided 105 with an interiorly projecting rib 18 engaging a groove 19 formed in the staves just beyond

the ends of the inturned flanges, whereby, when the ring is placed in position on the barrel, said rib will engage the groove and lock the ring on the head.

- 5 The stave ends are indicated at 20 and as shown in Figure 6, such ends lie flat throughout their height and circumference against the outer surfaces of the head flanges 14 which are of the same height. In my re-issue patent
10 10 previously referred to, the stave ends and the head flanges 14 were brought upward into a vertical position; or in other words, at substantially right angles to the plane of the head 13. In accordance with the present in-
15 vention however, I cause the stave ends 20 and head flanges 14 to assume a diagonal position or a position at acute angles to the vertical and to the plane of the head 13. This construction causes the stave ends 20 and
20 flanges 14 to diverge outwardly away from the sides and ends of the barrel and a wedge or inclined plane effect is secured by the seating of the bevel flange 14 upon the bevel stave ends 20. By forcing the heads 13 inwardly of the barrel, a tighter seating between parts 20 and 14 is secured.

In like manner the outer and inner walls 15 and 17 of the locking chime ring are caused to assume a like diagonal position whereby to embrace respectively the stave ends 20 and the flange 14 so as to lie in contact throughout with these parts.

There results from this construction a substantially V-shaped crimp 21 formed by the barrel staves and stave ends which is brought about without the requirement for any offsetting of the ends with respect to the staves. The locking ring 16 conforms to this crimp 21 and is thus held against casual outward creeping.

The new construction is stronger, more durable, less apt to leak or be displaced locally or generally.

Referring to Figure 7, the staves 5 are of

substantially the same construction, having flanges which form a T when brought together. In this form of the invention, the locking strip is also in the form of a T-iron. The locking strip is indicated at 10^a, the flanges at 11^a and the outwardly extending edges at 25. These edges or projecting portions 25 extend along the sides of the flanges 6 of the staves and interlock therewith.

It will be obvious that many changes in the construction, combination and arrangement of parts could be made, which could be used without departing from the spirit of my invention, and I do not mean to limit the invention to such details, except as particularly pointed out in the claim.

Having thus described my invention, what I claim and desire to secure by Letters Patent of the United States is:—

An all metal barrel, comprising a series of staves having outwardly flared ends, and inwardly turned side flanges terminating short of said ends, locking strips of the same length as said flanges slidably engaging said flanges, pan shaped dished metal heads each having a flat base and sides flaring outward in the form of a truncated cone, with the circular angled edge of the head directly engaging the circular angled line of bend between the main body part and the flared out ends of the staves, each head having its base resting on the ends of said flanges, and its tapering sides fitting snugly between the flared out ends of said staves, with a cap for holding each head in position provided with an inwardly turned tapering portion having its free end abutting against the barrel head, said cap having its outer portion bent over the free ends of the staves and over the outer perimeter of the dished head and bent downwards to engage into and project below the groove formed at the base of the outward flare of the staves.

JAMES HENRY GEORGE.
